UNITED STATES PATENT OFFICE.

HARRY L. BARRICKMAN, OF RICHWOOD, WEST VIRGINIA, ASSIGNOR TO JAMES S. JOHNSON, OF RICHWOOD, WEST VIRGINIA.

ROD-CO尤PLING.

1,003,973.

Specification of Letters Patent. Patented Sept. 26, 1911.

Application filed March 6, 1911. Serial No. 612,590.

To all whom it may concern:

Be it known that I, HARRY L. BARRICKMAN, a citizen of the United States, residing at Richwood, in the county of Nicholas and 5 State of West Virginia, have invented a new and useful Rod-Coupling; and I do hereby declare the following to be a full, clear, and exact description of the invention, such as will enable others skilled in the art 10 to which it appertains to make and use the same.

This invention relates to rod couplings and has special reference to that type of couplings which are designed to effect a detachable or separable connection between the 15 sections of sucker-rods, such as are employed with pumps for deep oil wells. It is frequently necessary to remove pumps of this character for the purpose of cleaning, thus 20 requiring the uncoupling of the sucker-rod at each joint. In the old type of sucker-rods, the sections are joined together by threaded connections. When disconnecting the various sections, considerable difficulty 25 is frequently experienced in the coupling and uncoupling of the rod sections.

The present invention aims as its primary object to provide an improved construction of coupling, which obviates the objections 30 to the ordinary screw joint, while, at the same time, materially expediting the disconnecting of the various sections.

A further object of the invention is to provide a novel form of coupling, which 35 will prevent the possibility of the rod sections becoming uncoupled while in the well.

In the drawings, however, there is only disclosed one form of the invention, but, in practical fields, this form may require certain 40 alterations, to which the applicant is entitled provided the alterations are comprehended by the appended claim.

The invention comprises further features and combinations of parts hereinafter set 45 forth, shown in the drawings, and claimed.

In the drawings:—Figure 1 is a perspective view of a portion of a sucker-rod, showing the sections thereof connected by the improved joint. Fig. 2 is a sectional view 50 on line 2—2 of Fig. 1. Fig. 3 is a sectional view similar to Fig. 2, with the exception that the parts of the joint and the sections of the sucker-rod are shown as dis-assembled. Fig. 4 is a transverse sectional view on line 55 4—4 of Fig. 2.

Referring to the drawings more specifically, 1 designates a sucker-rod. In the present instance, there are only two sections 2 and 3 of the sucker-rod shown. The adjacent ends of the sections 2 and 3 are correspondingly recessed, as shown at 4 and 5, thus affording the tongues 6 and 7. The adjacent faces of the tongues 6 and 7 are correspondingly inclined, as shown at 8, so as to prevent the disconnection of the two 60 sections, when the sleeve 9 is arranged as shown in Fig. 2. The tongues 6 and 7 are received by the recesses 4 and 5, in the manner shown in Fig. 2. The faces 10 and 11 of the tongues are provided with recesses 12 65 and 13. The recess 12, however, registers with the recess 14 of the section 2 of the rod, while the recess 13 registers with the recess 15 of the section 3 of the rod. The sleeve 9 fits telescopic over the adjacent 70 end portions of the sections 2 and 3 of the sucker-rod, as shown in Fig. 2. The inner circumference of the sleeve 9 is provided with oppositely arranged elongated recesses 16, adapted to receive the keys 17. However, the ends of the elongated recesses are closed, as shown at 18, so as to prevent displacement of the sleeve 9, that is, when the sleeve 9 is rotated to the position, as shown 75 in Fig. 2. The registered recesses 12, 13, 14 and 15 receive the offset portions 19 of the keys 17, as shown in Fig. 2, so as to also 80 prevent the disconnection of the sections of the sucker-rod. The inclined faces, however, constitute the main means for preventing 85 the sections of the rod from disconnecting. 90

In assembling the coupling for the two sections of the sucker rod, the two sections 2 and 3 are brought together, so that the 95 recesses 4 and 5 of the sections will receive the tongues 6 and 7, as shown in Fig. 2. After the sections 2 and 3 are thus assembled, the keys 17 are adjusted, so that their portions 19 will enter the recesses 12, 13, 14, and 15. 100 Subsequently the sleeve 9 is passed over the section 3 of the sucker rod, until the keys 17 enter the recesses 16, by way of the openings 16^a, shown in Figs. 1, 3 and 4. After the sleeve is thus arranged, a partial rotary 105 movement is imparted to it, until the closed portions, as shown at 18 of the recesses 16, are brought in front of the large ends of the keys 17, which will hold the various parts 110 of the coupling assembled. To disconnect

the parts of the coupling a partial, rotary movement is imparted to the sleeve 9 in a reverse direction, until the keys 17 are in registration with the openings 16^a, after 5 which the sleeve may be pushed back off of the key 17, so that the keys may be removed, after which the two sections 2 and 3 may be separated.

From the foregoing, in connection with 10 the drawings hereunto annexed, it will be noted that a novel form of rod coupling has been produced and one which will permit the disconnecting of the rod sections, without experiencing very much difficulty, and which 15 will also prevent the gradual disconnecting of the sections of the rod while in the well. This novel form of coupling has been found to be practical, simple in construction and cheap to manufacture.

20 The invention having been set forth, what is claimed as new and useful is;—

In combination, a pair of rod sections having their adjacent end portions provided with correspondingly shaped recesses and tongues, the tongues and the rod sections 25 having registering recesses, keys having offset portions extended into the registering recesses, a sleeve fitted telescopically over the joined ends of the rod sections and the keys, said sleeve having inwardly projecting annular flanges to prevent longitudinal movement of the sleeve, said sleeve being partially rotatable to bring the flanges adjacent the ends of the keys.

30 In testimony whereof I have signed my name to this specification in the presence of two subscribing witnesses.

HARRY L. BARRICKMAN.
